[57] CLAIM

The ornamental design for a towel-like wiper dispenser, as shown and described.

DESCRIPTION

FIG. 1 is a top, front and right side perspective view of a towel-like wiper dispenser showing my new design;

FIG. 2 is a rear elevational view thereof;

FIG. 3 is a right side elevational view thereof;

FIG. 4 is a bottom plan view thereof;

FIG. 5 is a top plan view thereof; and,

FIG. 6 is a left side elevational view thereof.

The broken-line disclosure of the towel like wipers in the views is for illustrative purposes only and forms no part of the claimed design.

FIG. 1

FIG. 2

FIG. 3

FIG. 4

FIG. 5

FIG. 6
